Patented Nov. 26, 1974

233,721

PLASTIC FORK

Hubert E. Christian, and David W. Lee, Phoenix, Ariz.,
assignors to Dart Industries Inc., Los Angeles, Calif.

Filed May 21, 1973, Ser. No. 362,355

Term of patent 14 years

Int. Cl. D7—03

U.S. Cl. D7—138

FIG.—1

FIG.—2

FIG.—3

FIG.—4

FIG.—5

FIG. 1 is a top plan view of a plastic fork showing our new design;

FIG. 2 is a bottom plan view thereof;

FIG. 3 is a side elevational view thereof;

FIG. 4 is a front end view thereof;

FIG. 5 is a rear end view thereof; and,

FIG. 6 is a cross-sectional view thereof, taken along the line 6—6 of FIG. 2.

We claim:

The ornamental design for a plastic fork, substantially as shown and described.
